UNITED STATES PATENT OFFICE.

MATHIAS WALTER, OF PATERSON, NEW JERSEY.

LEASE-REED.

No. 881,169.

Specification of Letters Patent. Patented March 10, 1908.

Application filed March 10, 1906. Serial No. 305,291.

To all whom it may concern:

Be it known that I, MATHIAS WALTER, a citizen of the United States, residing at Paterson, in the county of Passaic and State of New Jersey, have invented certain new and useful Improvements in Lease-Reeds, of which the following is a specification, reference being had therein to the accompanying drawing.

10 My invention relates to lease reeds used for warping and consists of dents of novel construction and the arrangement of the same in a reed.

The objects of my invention are to provide a reed that may be used as a single or a double reed; that may be used for the crossing of a single thread or filament; or for the crossing of sets consisting of a plurality of threads or filaments; that will facilitate the 15 process of warping and the passing of the threads through the reed; that will reduce the wear caused by passing the thread in an indirect line from the bobbins on the creel-frame and through the reed; and to provide a 20 dent that will permit the thread to pass through the lease reed in a direct line from the creel-frame to reduce the friction and facilitate the operation of warping.

Further objects of my invention are to 30 construct a reed that will be simpler, less expensive, more durable and less apt to cut or wear the thread.

These objects I accomplish by my invention which is illustrated in the accompanying 35 drawings, in which similar numerals indicate like parts in the various figures.

Figure 1 is a view showing various combinations of dents; the left hand side of said figure showing dents, some having eyes opening to the right and some having eyes opening to the left with intermediate eyeless dents, some slanting to the right and some to the left; while the right hand side of said figure shows dents only, one set having the 40 eyes opening to the right, the other set having eyes opening to the left, the dotted lines —a—a— and —a'—a'— on the left hand half of said figure and the right hand half of said figure, respectively, representing the 45 central point of a reed. Fig. 2 is a cross-section on line —A—A, of Fig. 1, showing the threads —s—s— passing through the right and left eyes or openings without friction, in radial lines directly from the creel-frame.

Fig. 3 represents a side view of one of my 55 improved dents.

In the drawings —1— is the frame of the reed in which the dents are secured together. The dents having eyes —3— are represented by the numeral —2—. The eyes —3— are 60 formed by pressing the sides —4— and —5— outwardly in opposite directions, as illustrated in Figs. —3— and —2—, so as to form an opening through which the thread —8— may pass in a radial direction, towards 65 the right or towards the left, as required.

The eyeless dent is represented by the 70 numeral —6— and the greater portion thereof may be bent either to the right or to the left to permit the passage of the thread unobstructed in a radial direction, or for the same purpose the eyeless dent may be secured in the frame —1— in a slanting or oblique position.

A reed of my construction, provided only 75 with my improved eye-dents requires for a cross of a single thread or alternate threads only half the number of dents that are required in a so-called single reed; and a reed embodying my invention will perform the 80 function of a so-called double reed with two thirds of the dents required by the double reed now in vogue.

As usually constructed, reeds have eyes 85 formed by soldering together two adjacent dents in two places, for a single reed; and for a double reed, three adjacent dents are soldered together, leaving a central opening or eye. In the single reed, as usually constructed, there is a clear space between each 90 pair of dents that are soldered together and in a double reed two clear spaces between each set of dents so soldered together. The solder used being soft the friction of the thread frequently cuts it and the result is 95 undue wear upon the thread; but this cannot occur with my reed.

Any combination of eye-dents and eyeless dents may be formed without departing 100 from the spirit and scope of my invention.

Besides the threads —s— represented in the right hand portion of Fig. 2 as coming radially through the eye-dents, other threads pass similarly between said eye-dents.

When using my reed for a double cross, or 105 for a cross of a plurality of threads or sets of threads, a change may be made by removing a thread or threads from each set as required.

It is obvious that many combinations of dents may be made to accomplish the cross desired and it is not deemed necessary to show every such combination in the drawings.

While the most usual crosses in weaving are what is known as the single and double crosses, it is quite evident that my invention includes within its scope the scheme of carrying any number of threads or sets of threads above the plane or position occupied by other threads or sets of threads to make the cross desired, all threads passing in a radial direction through the reed when drawn from the bobbins on the creel-frame.

With this description of my invention, what I claim as new, and desire to secure by Letters Patent, is:—

1. In a lease-reed, the combination with dents, some having openings there-through

passing obliquely to the right, and some having openings passing there-through obliquely to the left, of eyeless dents, some arranged obliquely, slanting to the right, and some arranged obliquely, slanting to the left, and a frame in which said dents are secured, substantially as set forth.

2. In a lease reed, the combination with the frame, of dents therein provided with obliquely facing openings, the dents on one side of said frame being reversely mounted with respect to those on the other side of said frame, in such a way that said oblique openings shall face toward the center of said reed.

In testimony whereof I affix my signature in presence of two witnesses.

MATHIAS WALTER.
